UNITED STATES PATENT OFFICE.

ROBERT DEMPSTER, OF BUFFALO, NEW YORK, ASSIGNOR OF ONE-HALF
HIS RIGHT TO JOHN M. COMSTOCK, OF SAME PLACE.

IMPROVEMENT IN STEAM-BOILERS.

Specification forming part of Letters Patent No. 170,348, dated November 23, 1875; application filed
October 8, 1875.

To all whom it may concern:

Be it known that I, ROBERT DEMPSTER, of the city of Buffalo, in the county of Erie and State of New York, have invented certain new and useful Improvements in Steam-Boilers, which improvements are fully set forth in the following specification, reference being had to the accompanying drawings.

The object of this invention is to provide a simple, convenient, and durable portable steam-boiler; and it consists of a removable annular steam-chamber, forming the top of the boiler, and the opening through which the fuel is introduced; an annular water-space compartment, which forms the outer and inner shell of the sides of the boiler; and inside annular water-space compartment, placed on a level, or nearly so, with the grate-surface, and arranged so that it forms the lower part of the fuel and combustion chamber; the whole being arranged and combined with the necessary circulating and connecting tubes, as will be more clearly hereinafter shown by reference to the said drawings, in which—

Figure 1 is a side elevation of the boiler complete, and Fig. 2 a vertical section through the center of the same.

A represents the removable annular steam-chamber, forming the top of the boiler. B, in Fig. 1, is the cover; and C, in Fig. 2, the opening through which the fuel is introduced. D D' are tubular connections for holding the chamber A to the boiler, and for affording communication between them, all of said parts being screwed or otherwise put together, so as to be easily connected or disconnected,

and so as to answer for steam-pipes for connecting with the engine or for other purposes. E is the outer annular water-chamber, forming the body of the boiler, and F the inside annular water-chamber, which also answers for a fire-box. The upper parts of both chambers are connected by the tubes G G, and the lower parts by the tubes H and J J', J being made to serve for a feed-pipe, and J' for a blow-off pipe. K represents the smoke-stack, and K' in dotted lines, Fig. 2, the opening leading thereto. L is the upper combustion-chamber. M is a partition separating the ash-pit and all that portion below the grate from the flues N N. The direction of the currents of the products of combustion is plainly shown by the arrows. The heat and gases as they rise and heat the upper part of the combustion-chamber are drawn down by the force of the draft between the annular water-spaces and out into the smoke-stack. P represents the door leading to the ash-pit, and Q a lever for shaking the grate.

I claim as my invention—

The removable steam-chamber A, provided with the opening C, tubes or pipes D D', in combination with the annular water-chamber E, forming the body of the boiler, connecting-pipes G G, annular water-chamber, and fire-box F, pipes or connections J J', and partition M, all arranged substantially as and for the purposes described.

ROBERT DEMPSTER.
